UNITED STATES PATENT OFFICE.

FRANK S. MYERS, OF REDFIELD, SOUTH DAKOTA.

PACKAGE-FASTENER.

No. 893,859.

Specification of Letters Patent.

Patented July 21, 1908.

Application filed February 28, 1908. Serial No. 418,344.

To all whom it may concern:

Be it known that I, FRANK S. MYERS, a citizen of the United States, residing at Redfield, in the county of Spink and State of South Dakota, have invented a new and useful Package-Fastener, of which the following is a specification.

This invention relates to package fasteners and more particularly to that class of fastener especially designed for holding letters and other mail matter in packages or bundles while being transported through the mails.

The object of the invention is to provide a simple and inexpensive device of this character capable of being quickly applied to or removed from a bundle of letters or the like and by means of which the letters in the bundle may be securely held against accidental separation during transportation.

20 A further object is to provide a package fastener formed from a single piece of wire bent upon itself to produce intersecting arms having means for engagement with a cord, chain or other flexible binding medium.

25 A still further object of the invention is generally to improve this class of devices so as to increase their utility, durability and efficiency.

Further objects and advantages will appear in the following description, it being understood that various changes in form, proportions and minor details of construction may be resorted to within the scope of the appended claims.

35 In the accompanying drawings forming a part of this specification: Figure 1 is a perspective view of a package of mail matter showing a fastener constructed in accordance with my invention applied thereto. Fig. 2 is a perspective view of the fastener detached. Fig. 3 is a detail side elevation of the clamping jaws.

Similar numerals of reference indicate corresponding parts in all of the figures of the drawings.

The improved package fastener forming the subject matter of the present invention is preferably formed from a single piece of wire or other suitable material, one end of which is bent upon itself to form an eye or loop 5 terminating in an arm 6, the wire being thence bent upwardly and laterally to produce a guide loop 7 and thence extended laterally at an angle to the arm 6 and bent 55 downwardly to form a similar loop 8.

The loops 7 and 8 in conjunction with the

connecting bar 9 constitute a turning member for the cord, chain or other flexible binder indicated at 10, the wire after the loop 8 is formed being extended transversely across the arm 6 to form an intersecting arm 11, the wire being thence twisted to form superposed coils 12 constituting a clamping member, the end of the wire forming the clamping member being bent around the arm 6 and anchored thereto by means of an eye 13.

The end of the wire at the loop 5 is passed through the eye 13 and is bent downwardly in engagement with the arms 11 and 14 to produce an eye 15 thus securely locking the several arms of the fastener at approximately the center of the latter.

In using the fastener one end of the cord 10 is fastened in the eye 5 and thence passed longitudinally around the back of the bundle 75 of mail matter A and over the front thereof, and thence passed under the connecting bar 9 into engagement with the loops 7 and 8, thence passed around the back of the package and against the front, the end of the cord 80 or chain being wrapped around the bundle one or more times and inserted between the clamping members 12, as best shown in Fig. 1 of the drawing.

In order to detach the fastener it is merely 85 necessary to exert a slight lateral pull on the free end of the cord 10 when the latter will be released from the clamping members 12 so that the cord together with the fastener may be readily detached from the package of letters.

In Fig. 1 of the drawings the binder is in the form of a cord and in Fig. 2 a chain 16 is illustrated as the binding medium. If desired, however, a leather strap, metal band 95 or the like may be substituted for the cord or chain without departing from the spirit of the invention.

Attention is here called to the fact that one side of the upper spring jaw 12 is bent 100 upwardly at a slight angle to the mating jaw so as to assist in guiding the cord or chain between said jaws, that portion of the upper jaw at its juncture with the arm 11 forming a bearing surface for engagement with the cord when drawing the same around the bundle or package in the act of tying the latter.

From the foregoing description it will be seen that there is provided an extremely simple, inexpensive and efficient device admirably adapted for the attainment of the ends in view.

Having thus described the invention what is claimed is:

1. A package fastener having an attaching eye and provided with spaced loops connected by a diagonal bar, said loops and bar constituting a turning member, a binder having one end thereof secured to the eye, and a clamping member disposed on one side of the turning member for engagement with the opposite end of the binder.
2. A package fastener having an attaching eye and provided with spaced loops united by a diagonal connecting bar, said loops and bar forming a turning member, a flexible binder having one end thereof secured to the attaching eye, and a clamping member formed of superposed spring jaws adapted to engage the opposite end of the binder, one of said jaws being disposed at a slight angle to the mating jaw to assist in guiding the binder between the same.
3. A package fastener including a body portion having intersecting arms two of which are formed with loops united by a connecting bar, said loops and bar forming a turning member, an attaching eye formed integral with the body portion, a flexible binder having one end thereof secured to the attaching eye, and a clamping member disposed on one side of the loop and turning member and adapted to engage the opposite end of the binder.
4. A package fastener including a body portion having intersecting arms two of which are bent to form guide loops united by a diagonal connecting bar, said loops and bar constituting a turning member, an attaching eye formed in the third arm, a flexible binder having one end thereof secured to the attaching loop, and a clamping member carried by a fourth arm and comprising superposed spring

jaws adapted to engage the adjacent end of the binder, there being a bearing surface disposed at the juncture of one of the clamping jaws and the adjacent arm for contact with the binder.

5. A package fastener formed of a single piece of wire one end of which is bent upon itself to form an attaching eye and thence bent to produce a plurality of intersecting arms two of which are provided with loops and connected by a diagonal bar, said loops and diagonal bar forming a turning member, a binder having one end thereof secured to the attaching eye, the wire forming one of the arms being bent to produce a clamping device for engagement with the opposite end of the binder.

6. A package fastener formed of a single piece of wire one end of which is bent to produce an attaching loop and thence extended to form a longitudinal arm terminating in an over-hanging loop, the wire at said loop being extended at an angle to the arm and bent to form a single loop, the wire after the last named loop is formed being extended across the longitudinal arm to produce a transverse arm and thence bent to form superposed spring clamping jaws, the end of the wire forming one of the jaws being bent around the longitudinal arm to produce an eye, and the wire forming the end of the attaching loop being extended through said eye and thence bent downwardly in engagement with the transverse arm.

In testimony that I claim the foregoing as my own, I have hereto affixed my signature in the presence of two witnesses.

FRANK S. MYERS.
